INFEED FOR GRINDING MACHINES

William L. Drown, Paxton, Mass., assignor to
Norton Company, Worcester, Mass., a corpora-
tion of Massachusetts

Application September 28, 1946, Serial No. 700,035

13 Claims. (Cl. 51—2)

1

The invention relates to grinding machines and more particularly to cylindrical grinding machines.

One object of the invention is to provide an improved cylindrical grinding machine for grinding cylindrical surfaces wherein the finished size may be automatically controlled with great accuracy. Another object is to improve the machine of U. S. Patent No. 2,267,391 to Astrowski. Another object of the invention is to provide a readily controlled automatic apparatus for rapidly moving the grinding wheel and the work relatively toward and away from each other. Another object is to provide automatically controlled and variable slow speed grinding wheel infeed during the grinding operation after rapid relative approach of the wheel and the work with automatic separation of the wheel and the work when desired work size is reached. Another object is to provide smooth grinding infeed action of the grinding wheel relative to the work at various grinding infeed speeds with or without automatic work size control within extremely fine limits of accuracy. Another object is to provide increased production in finish grinding. Another object is to provide apparatus of the character indicated which may be economically manufactured and compactly assembled on a standard grinding machine and which will give accurate and dependable operation over a long period of time.

Other objects will be in part obvious or in part pointed out hereinafter.

The invention accordingly consists in the features of construction, combinations of elements, and arrangement of parts, as will be exemplified in the structure to be hereinafter described, and the scope of the application of which will be indicated in the following claims.

In the accompanying drawings, in which is shown one of many possible embodiments of the mechanical features of this invention,

Figure 1 is a longitudinal sectional view of the apparatus of the invention mounted upon the wheel feed shaft;

Figure 2 is an end view of the apparatus;

Figure 3 is a vertical sectional view of the apparatus of the invention and associated mechanism together with a wiring diagram and a fluid diagram.

As conducive to a clearer understanding of the invention, it is noted that the illustrative embodiment discloses an improvement of a type of apparatus now commonly in use for moving the grinding wheel relative to the work. Such a ma-

2

chine has a work table upon which is mounted a headstock and a tailstock to hold a cylindrical work piece and rotate it against the grinding wheel for cylindrical grinding. Such a machine also has fluid pressure means for rapid infeed and retraction and for normal grinding infeed and slow grinding infeed.

The terms rapid infeed and retraction as used herein mean positioning of the grinding wheel relative to the work preparatory to grinding and, retracting it rapidly from the work when grinding is completed. The term "normal grinding infeed" means feeding the wheel against the work during rough grinding, and the term "slow grinding infeed" means feeding the wheel against the work for the final and finishing cuts.

According to the present invention additional fluid pressure means hereinafter described are provided whereby after the wheel slide has rapidly approached the work piece and is ready to grind, a very finely controlled smooth and accurate slow grinding infeed is provided with uniformity within close tolerances and with automatic stopping of the grinding infeed and rapid retraction of the wheel slide relative to the work when size is reached.

As illustrated in the drawings the machine of the invention comprises a base 10 which supports a wheel slide 11 for transverse movement thereon on the V-ways 12 which in turn rotatably supports a grinding wheel 13. The base 10 also supports a longitudinally movable work supporting table (not shown) which is arranged to slide on ways.

35 Work rotation

A cylindrical work piece 14 may be held between a power driven head stock and a tail stock mounted upon the longitudinally movable work supporting table (none of these being shown) so that it can be rotated against the grinding wheel 13 when the latter is in position to grind, and moved longitudinally across the grinding face of the wheel to grind a cylindrical surface on the work piece 14.

45 Grinding wheel drive mechanism

The grinding wheel 13 is mounted on a spindle 15 which is journaled in bearings in the top of the wheel slide 11, and it is driven by any convenient source of power such as an electric motor 17 which may be mounted on the wheel slide 11 to drive a pulley 18 mounted on the motor shaft 19, a belt 20 and a pulley 21 on the wheel spindle 15.

Grinding wheel rapid infeed mechanism

A half nut 25 depending from the under side of the wheel slide 11 and fastened to it engages a threaded portion 26 of a feed screw 27 which is rotatably connected to an enlarged portion 28 of a longitudinally slideable feed shaft 29 in bearings 30 in the base 10 of the machine. A hand wheel (not shown) on the front of the machine is connected to turn the feed screw 27. Rotation of the hand wheel in one direction feeds the wheel slide 11 and grinding wheel 13 into the work, and in the other direction retracts the wheel slide 11. For rapidly moving the grinding wheel 13 to and from a grinding position, fluid pressure means are provided comprising cylinder 31 which is either formed as an integral part of the base 10 or fixedly mounted thereon. The shaft 29 is aligned with the axis of the cylinder and serves as a piston rod. A piston 35 is slidably mounted within the cylinder 31 and is supported on a reduced end portion 36 of the piston rod 29. An end thrust bearing 38 is interposed between a shoulder 39 on the rod 36 and one end of the piston 35 and a second end thrust bearing 40 is interposed between the other end of the piston 35 and a nut 41 on the rod 36. It will be apparent that when the piston is moved endwise, it will transmit a feeding movement to the grinding wheel 13 through the rod 29, its enlarged portion 28, the feed screw shaft 27 and half nut 25 to move the wheel slide 11. The feed screw 27 is arranged so that it may be rotated relative to the piston 35 so that the operator, by manual rotation of the feed screw 27 may readily adjust the position of the grinding wheel 13 relative to the fluid pressure mechanism.

Grinding infeed mechanism

A fluid pressure actuated piston and cylinder mechanism 50 is provided in alignment with and assembled about an extended portion 51 of the feed shaft 29 for accurate control of grinding wheel infeed during the grinding operation and positive stopping upon grinding of the work piece to desired size.

A sleeve 55 is slidably mounted upon the extended portion 51 of the feed shaft 29. A piston 56 is mounted upon the sleeve 55 and held against a shoulder 57 on the sleeve 55 by means of a nut 58. Slidably mounted over the piston 56 is a cylinder 60 which is also slideable upon the sleeve 55 by means of packed fluid pressure tight holes 61 and 62 in the cylinder heads 63 and 64. Near the inner end of the sleeve 55 a threaded collar 66 having a split locking portion 67 is adjustably mounted on a threaded portion of the sleeve 55. On a threaded portion 69 on the outer end of the shaft 51 is adjustably mounted a collar 70 which has a split locking portion 71. A pair of bell crank arms 75 and 76 pivot about shafts 77 and 78 mounted in bosses 79 and 80 which are integral with the base 10 of the machine. The bell crank arms 75 and 76 have bearing surfaces 85 and 86 on the short ends thereof which ride against the face 87 of collar 66. On the ends of the long arms 88 and 89 of the bell crank arms 75 and 76 are rotatably mounted a pair of cam followers 90 and 91. These make contact with an outside conically shaped cam surface portion 100 of the cylinder 60.

When fluid pressure in the main cylinder 31 drives the piston 35 and hence the wheel slide 11 forward for rapid infeed, the collar 70 finally makes contact with the outer end 101 of the sleeve 55. The sleeve 55 cannot go any further in because the face 87 of collar 66 is riding against

surfaces 85 and 86 of the bell crank arms 75 and 76 which are in turn held in position by the cam followers 90 and 91 upon the cam surface 100 of the cylinder 60. However when fluid pressure is introduced into the left hand portion of cylinder 60 and exhausted out of the right hand portion, the cylinder 60 will move to the left along sleeve 55 and piston 56. This allows the cam followers 90 and 91 to roll down the cam surface 100 toward each other which in turn imparts a slight movement of bearing surfaces 85 and 86 to the left thus allowing collar 66, sleeve 55, collar 70, feed shaft 51 and wheel slide 11 to move very slightly to the left for a very fine grinding infeed while the grinding wheel is cutting the work. While a full head of fluid pressure may be maintained in the main cylinder 31 and cam actuating cylinder 60 all during the rapid infeed and grinding infeed cycle, it may be seen that rapid infeed is changed to slow grinding infeed when collar 70 makes contact with sleeve 55 and slow grinding infeed may be controlled by metering oil out of cylinder 60. A positive stop is provided when work size is reached by instantly reversing the flow of fluid pressure in both cylinders 31 and 60, as will be more fully explained.

Fluid pressure control

A fluid pressure control valve 105 is provided to regulate the admission of fluid to cylinders 31 and 60. This valve is preferably of the balanced piston type having a valve stem 106 and a plurality of valve pistons 107, 108, and 109 which are slidably mounted in the valve 105. The ports in the valve 105 are so arranged that fluid from a reservoir 112 is forced by a pump 113 through a conduit 114 into a valve chamber 115. As the valve stem 106 is shifted from one extreme to the other extreme position, the fluid flow may be changed from one side of piston 35 to the other to reverse the direction of movement of the wheel slide, and from one side of piston 56 to the other to reverse the direction of movement of cylinder 60. In the construction shown, with the valve stem 106 positioned to the left against spring 118, fluid under pressure enters through valve chamber 115 and goes to the right side of piston 35 through passage 120. It may also enter cylinder 60 at the left side of piston 56 through pipe 121 and check valve 122. Fluid is exhausted from the left side of piston 35 through passage 125, valve chamber 126 and back into reservoir 112 through pipe 127, hand adjusted valve 128, and also through pipe 129 and solenoid operated valve 130 which is kept normally open by spring 131.

Fluid is exhausted also from the right side of piston 56 through pipe 135, solenoid operated metering valve 136, pipe 137 and back to the reservoir 112 by way of passage 125, as described. This is the main valve setting for rapid and normal grinding infeed, to the left as shown. With rapid infeed to position the wheel, it is desirable to slow the action down somewhat just before collar 70 makes contact with sleeve 55 so as to avoid jarring of the cam actuating mechanism. To this end the solenoid operated valve 130 is provided. While normally open to allow rapid exhaust from the main cylinder 31 during infeed, it is momentarily closed just before collar 70 makes contact with sleeve 55, as will be more fully explained. When valve 130 is closed, exhaust fluid is metered through hand adjusted valve 128 to slow down the infeed action just before collar 70 makes contact with sleeve 55. The movement of cylinder 60 is delayed while

piston 35 is operated for rapid infeed because solenoid operated metering valve 136 is normally almost closed to allow only a very fine stream of fluid to pass through it. It has a stem 140 having a wedged slot 141, which when it is normally positioned to the left as shown, meters fluid through it at a slow rate which is adjustable by set screw 142 to allow only a very slow grinding infeed by slow cam action of cylinder 60 to the left. When valve stem 140 is to the right, fluid is metered at a more rapid rate for normal grinding infeed. Positive stopping of infeed is instantaneous and retraction of the grinding wheel is immediately brought about by reversing the flow of fluid through the piston and cylinder assemblies by reversing solenoid operated valve 105.

During retraction of both the main piston 35 and the cam actuating cylinder 60, fluid delivered from the reservoir 112 by pump 113 under pressure passes through valve chamber 115, passage 125 to the left side of piston 35. It also passes through line 137 and a check valve 143 which is provided in a shunt pipe 144 across valve 136 between lines 137 and 135, and into cylinder 60 at the right side of piston 56 under full head to retract cylinder 60 rapidly to the right to its initial starting position. Cylinder 31 exhausts from the right side of piston 35 through line 120, valve 105 at the right side of piston 108 and down through pipe 145 and hand adjusted metering valve 146 to the reservoir. Valve 146 is provided to adjust the speed of retraction of piston 35, and the exhaust from the left side of piston 56 in cylinder 60 also passes through it. This exhaust rate from the left side of piston 56 is also adjustable where it passes through hand adjusted valve 147 into line 120. While the speed of rapid infeed and grinding infeed may be controlled by closing valves 130 and 136, the speed of retraction is unaffected by these valves which are bypassed when the main valve 105 is reversed for retraction so that retraction speed may be set as high as desired by hand operated valves 146 and 147.

Electrical control

The main solenoid operated control valve 105 is normally positioned by spring 118 to retract the wheel slide from the work. By energizing its solenoid 150, rapid and grinding infeed are effected. This is done by moving a main operating switch lever 155 to the left which closes main switch contacts 156 and 157. An electric circuit is then completed across wires 158 and 159 from an alternating current power source which may be one hundred and ten volts. The current from wire 158 runs through wire 160, switch contacts 156 and 157, relay operated switch 161 which is normally closed, through relay 162, wire 163 and through wire 164 to wire 159 to energize relay 162. Relay operated switch 165 is then closed to complete the circuit from wire 160 by way of wires 166 and 167 through solenoid 150 to energize it and through wire 164 to wire 159. When relay 162 was energized it also closed relay operated switch 168 to form a holding circuit so that when hand pressure is released on lever 155 to reopen contact 157 which is normally open, the circuit energizing solenoid 150 will nevertheless remain closed. The wheel slide 11 and shaft 51 now start rapidly to the left. Just before collar 70 makes contact with the end 101 of sleeve 55, it engages arm 169 of limit switch 170 to close it. This momentarily energizes solenoid 171 to close valve 130 and slow the speed of movement of the

wheel slide 11 to the left as collar 70 makes contact with sleeve 55. The circuit is completed from wire 158 through wires 172, 173, solenoid 171, wire 174, switch 170 and wire 175 to wire 159. Just as collar 70 makes contact with sleeve 55, it rides over arm 169 to reopen limit switch 170 and valve 130. At this instant collar 70 also engages arm 176 of limit switch 180 to energize solenoid 181 and open valve 136. The circuit is completed from wires 158, 172, switch 180, wire 182, solenoid 181, wire 184, relay operated switch 185 and wire 186 to wire 158. Relay switch 185 is normally closed, and trip switch 180 remains closed during the remainder of the grinding infeed cycle.

15 A standard electrical work sizing gage 190 is provided such as that disclosed in U. S. patent to S. A. Foster, No. 2,267,559, having double contacts which are normally open and which close successively as work size is reduced. The first contact to close has terminals 191 and 192 and is adjusted to close when work size is reduced to the point when it is desired to change from normal grinding infeed rate to slow grinding infeed rate. The second pair of contacts have terminals 193 and 194 and are adjusted to close when finished size of work is reached. As work size is reduced at normal grinding infeed speed, the first contacts with terminals 191 and 192 close to complete the circuit from wire 158 across terminals 191 and 192, relay 195, and wire 186 to wire 159. This energizes relay 195 to open switch 185. Solenoid 181 is deenergized and valve 136 closes to meter oil at slow grinding infeed rate. As finished work size is reached the second pair of contacts of gage 190 with terminals 193 and 194 close to complete the circuit across terminals 193 and 194 from wire 158 through wire 196, relay 200 and wire 164 to wire 159. This energizes relay 200, opens relay operated switch 161 to break the circuit through relay 162, thereby allowing relay operated switch 165 to open and deenergize solenoid 150. The main valve 105 is then reversed, grinding infeed comes to a positive instantaneous stop and the wheel 13 is retracted from the work 14.

45 To operate the machine, starting with the grinding wheel in retracted position, I place a cylindrical work piece 14 in the headstock and footstock and set the gage 190 to change the grinding infeed from normal to slow or finish 50 grinding rate at the required size, and to stop the grinding at the required finished size. I start the work piece rotating and throw starting switch lever 155 to the left for an instant. The wheel 13 starts rapidly toward the work (to the left, as shown). As collar 70 hits arm 69 of switch 170, the motion is slowed momentarily until collar 70 makes contact with the end 101 of sleeve 55. At that instant collar 70 actuates arm 176 to close switch 180 and open metering valve 136. The wheel now makes contact with the work and grinds at normal grinding infeed speed as cylinder 60 moves to the left until the gage contacts across terminals 191 and 192 close. This shuts down metering valve 136 so that only 55 a small stream of oil is exhausted from cylinder 60, which continues at a slower rate to the left to allow a finish grinding infeed rate. When work size is reached, the gage contacts across terminals 193 and 194 close. Valve 105 is instantly reversed to retract the wheel from the work and cylinder 60 is repositioned so that a new cycle of operation may be started. A new work piece may then be inserted and the operation repeated.

70 75 The mechanism of the invention provides ex-

tremely smooth and finely controlled grinding in-feed action since there are no couples set up along the feed shaft due to the balanced construction of the cam surfaces about the feed shaft and of the bell crank arms, which eliminates any side stresses. Since the mechanism is mounted concentrically about an extension of the standard feed shaft, one of its great virtues is that it can be mounted upon any standard grinding machine because of its compactness.

While the invention is particularly applicable to a cylindrical grinder having work centers, it may also be applied to a crank grinder wherein the work piece is held by so-called pot chucks and wherein the normal grinding infeed grinds the shoulders of a crank pin.

It will thus be seen that there has been provided by this invention an apparatus in which the various objects hereinabove set forth together with many thoroughly practical advantages are successfully achieved.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine a cross slide mounted on ways, a feed shaft connected to said cross slide, means to move said cross slide in either direction, abutment means to control final movement of said cross slide in one direction including a collar on said shaft, a sleeve slidably on said shaft to abut said collar after movement of said shaft in one direction, a piston fixedly mounted on said sleeve, a cylinder slidably mounted on said piston and sleeve having cam surfaces to actuate said abutment means and fluid pressure means to actuate said cylinder.

2. In a grinding machine a cross slide mounted on ways, a feed shaft connected to said cross slide, fluid pressure means to move said cross slide in either direction and to urge it in one direction, abutment means to control final movement of said cross slide in one direction including a collar on said shaft, a sleeve slidably on said shaft to abut said collar after rapid movement of said shaft in one direction, a piston fixedly mounted on said sleeve, a cam actuating cylinder slidably mounted on said piston and sleeve having cam surfaces, bell crank arms abutting said sleeve and actuated by said cam surfaces and fluid pressure means to actuate said cylinder in timed relation with the movement of said cross slide.

3. In a grinding machine a cross slide mounted on ways, a feed shaft connected to said cross slide, fluid pressure means to move said cross slide rapidly to an abutment in the direction of feed to urge it against said abutment and to retract it therefrom, abutment means to control final movement of said cross slide in one direction including a collar on said shaft, a sleeve slidably on said shaft to abut said collar after rapid movement of said cross slide in the direction of feed, a piston fixedly mounted on said sleeve, a cam actuating cylinder slidably mounted on said piston and sleeve having cam surfaces thereon, means actuated by said cam surfaces and abutting said sleeve to allow said sleeve to move in the direction of feed and to reposition it in the other direction and fluid pressure means to actuate said cylinder in timed relation with the movement of said cross slide.

4. In a grinding machine a cross slide mounted on ways, means to move said cross slide rapidly in both directions and to urge it steadily in one direction, abutment means to allow said cross slide to move very slowly in one direction including a shaft connected to said cross slide, a collar on said shaft, a sleeve slidably on said shaft to abut said collar, a piston mounted fixedly on said sleeve, a cylinder slidably on said piston and sleeve having cam surfaces longitudinally thereof, bell crank arms actuated by said cam surfaces and abutting said sleeve, fluid pressure means to actuate said cylinder in either direction whereby movement of said cylinder in one direction allows said bell crank arms to close and allow said cross slide to move.

5. In a grinding machine a cross slide mounted on ways, fluid pressure means to move said cross slide rapidly in either direction and to urge it steadily in one direction, abutment means to control final movement of said cross slide in one direction after rapid movement in that direction including a shaft connected to said cross slide, a collar on said shaft and a sleeve slidably mounted on said shaft to abut said collar, bell crank arms abutting said sleeve, and cam means to rock said bell crank arms.

6. In a grinding machine a cross slide mounted on ways, fluid pressure means to move said cross slide rapidly in either direction and to urge it steadily in one direction, abutment means to allow said cross slide to move slowly in one direction after rapid movement in that direction including a shaft connected to said cross slide, a collar on said shaft and a sleeve slidably mounted on said shaft to abut said collar, bell crank arms abutting said sleeve, cam means to rock said bell crank arms, fluid pressure means to actuate said cam means and means to control said fluid pressure means in timed relation with reduction of work size.

7. In a grinding machine a cross slide mounted on ways, fluid pressure means to move said cross slide rapidly in either direction and to urge it steadily in one direction, abutment means to allow said cross slide to move slowly in one direction after rapid movement in that direction including a shaft connected to said cross slide, a collar on said shaft and a sleeve slidably mounted on said shaft to abut said collar, bell crank arms abutting said sleeve, cam means to move said bell crank arms including a fluid pressure piston fixedly mounted on said sleeve, a cylinder slidably over said piston having cam surfaces, valves to control the flow of pressure in said cylinder in timed relation with reduction of work size, solenoids to operate said valves and switches to operate said solenoids.

8. In a grinding machine a cross slide mounted on ways, fluid pressure means to move said cross slide rapidly in either direction and to urge it steadily in one direction, abutment means to allow said cross slide to move slowly in one direction after rapid movement in that direction including a shaft connected to said cross slide, a collar on said shaft and a sleeve slidably mounted on said shaft to abut said collar, bell crank arms abutting said sleeve, cam means to rock said bell crank arms and means momentarily to slow the rapid movement of said cross slide in one direction just before said collar engages said sleeve.

9. In a grinding machine a cross slide mounted on ways, means to move said cross slide rapidly in either direction and to urge it steadily in one direction, abutment means to control final move-

ment of said cross slide in one direction after rapid movement in that direction including a shaft connected to said cross slide, an abutting member on said shaft and a sleeve slidable on said shaft to abut said abutting member, cam means abutting said sleeve to move it and fluid pressure means to actuate said cam means.

10. In a grinding machine a cross slide mounted on ways, means to move said cross slide rapidly in either direction, abutting means to allow a very finely controlled final movement of said cross slide in one direction after rapid movement including a shaft connected to said cross slide, an abutting member on said shaft, a sleeve slidable on said shaft to abut said abutting member, abutting members to abut said sleeve, a fluid pressure cylinder slidable on said sleeve having cam surfaces to actuate said abutting members and valves to control the flow of fluid pressure in said cylinder in timed relation with rapid movement of said cross slide and with reduction of work size.

11. In a grinding machine a cross slide mounted on ways, abutting means to allow a very finely controlled final movement of said cross slide in one direction after rapid movement including a shaft connected to said cross slide, an abutting member on said shaft, a sleeve slidable on said shaft to abut said abutting member, abutting members to abut said sleeve, a fluid pressure cylinder slidable on said sleeve having cam surfaces to actuate said abutting members, a valve to meter the fluid pressure from said cylinder, a solenoid to operate said valve and a trip switch actuated by said shaft to operate said solenoid.

12. In a grinding machine a cross slide mounted on ways, fluid pressure means to feed said cross slide and retract it rapidly, abutting means to allow a very finely controlled grinding infeed movement of said cross slide after rapid infeed in-

cluding a shaft connected to said cross slide, an abutting member on said shaft, a sleeve slidable on said shaft to abut said abutting member, abutting members to abut said sleeve, a piston on said sleeve, a cylinder slidable on said piston and sleeve having cam surfaces to actuate said abutting members, a valve to admit fluid pressure to said fluid pressure means and to said cylinder and to reverse the direction of flow thereof to retract said cross slide and said cylinder when final work size is reached.

13. In a cylindrical grinding machine a rotatable grinding wheel, a cross slide, automatic means to move said cross slide rapidly to position the wheel relative to the work for grinding, slowly at various speeds for normal and slow grinding infeed and for rapidly separating the work and the wheel when finished work size is reached including a shaft connected to said cross slide, a fluid pressure cylinder, a piston in said cylinder and mounted on said shaft, an abutting member on said shaft, a sleeve on said shaft to abut said abutting member, bell crank arms to abut said sleeve, a cam to limit motion of said bell crank arms, a fluid pressure piston fixedly mounted on said sleeve and a cylinder slidable on said piston and sleeve to actuate said cam in timed relation with rapid motion of said cross slide and with reduction of work size.
